(57) **CLAIM**

The ornamental design for a remote control, as shown and described.

DESCRIPTION

FIG. 1 is a front perspective view of a remote control design showing my new design.

FIG. 2 is a front view of a remote control.

FIG. 3 is a rear view of a remote control.

FIG. 4 is a left side view of a remote control.

FIG. 5 is a right side view of a remote control.

FIG. 6 is an enlarged top view of a remote control.

FIG. 7 is an enlarged bottom view of a remote control.

FIG. 8 is a rear perspective view of a remote control; and, FIG. 9 is an enlarged view of a remote control taken from the circle part in FIG. 3.

The broken lines in FIGS. 7 and 9 depict portions of the remote control that form no part of the claimed design.

The dash-dash broken lines indicate where the enlargements have been taken, and form no part of the claimed design.
